DESIGN FOR A LIGHTING FIXTURE

Clyde D. McCann, Des Moines, Iowa

Application December 9, 1940, Serial No. 97,187

Term of patent 14 years

To all whom it may concern:

Be it known that I, Clyde D. McCann, a citizen of the United States and resident of Des Moines, Polk County, Iowa, have invented a new, original, and ornamental Design for a Lighting Fixture, of which the following is a specification, reference being had to the accompanying drawing, forming a part thereof.

Fig. 1 is a side elevational view of the lighting fixture showing my new design; and

Fig. 2 is an end elevational view thereof.

I claim:

The ornamental design for a lighting fixture, substantially as shown.

CLYDE D. McCANN.
